John S. Hadden

John L. Hadden, of Philadelphia, Pennsylvania.
Letters Patent No. 2072-Dated May 30, 1865.
Design for a Boiler Lid.

DES. 2072

The schedule referred to in this letter patent and making part of the same.

Shall show it may concern:

Be it known that I, John L. Hadden, of the City of Philadelphia, in the State of Pennsylvania, have invented or produced a new and original design for the cover or oblong lid of a wash boiler; and I do hereby declare that the following is a full and exact description of the same, reference being had to the accompanying drawings making part of this specification, in which figure 1 represents the upper side of an oblong lid of a wash boiler having the said design thereon, and figure 2 a vertical section of the same, cut on the dotted line of fig. 2 of figure 1, like letters of reference indicating the same parts both in both figures.

The said design consists of an oval or oblong lid of thin metal having its boundary edge raised or bent so as to present on its upper side a convex head of a semi-circular form in its transverse section, while the part which is surrounded by the said head presents a surface raised gradually therefrom towards the middle of the lid.

In the drawings figure 1 is the lid, and 2 the head. The lid is oblong or oval, as seen in figure 1, and presents on its upper surface, the raised head 2 of the semi-circular form in its transverse section, surrounding the gradually raised enclosed portion, as represented in the drawings.

What I claim as new and desire to secure by Letters Patent is The design for a oblong lid for a wash boiler, as shown and described.
